Patented Apr. 3, 1928.

1,664,991

UNITED STATES PATENT OFFICE.

RICHARD OLDS, OF WALKERVILLE, AUSTRALIA.

MACHINE FOR FLESHING FURRED SKINS.

Application filed January 14, 1926, Serial No. 81,123, and in Australia August 3, 1925.

My invention relates to improvements in machines for fleshing furred skins, the object of the same being to provide means whereby a greater area of the skin can be exposed to the cutting knives than is at present the case with machines at present in use, and also to provide means whereby the depth or thickness of the cut can be evenly adjusted.

- 10 In carrying my invention into effect I provide a guard preferably in the form of a cylindrical casing having bearings at each end, but being open longitudinally at one side. This casing is furnished with a central rotatably mounted spindle upon each end of which there is a spider or other supporting element for carrying a series of straight knives. The spindle is preferably mounted on a ball bearing device so that it may 15 rotate with but little friction and can be furnished with a pinion wheel or sprocket wheel or other driving device at one end so that it may receive rotary motion from a driving element.
- 20 Upon each side of the open portion of the guard or cylinder I mount adjustable guides which are capable of sliding in grooves and are adapted to increase or decrease the relatively exposed area of the 25 knives so that the cut can be varied from a comparatively slight shaving to any predetermined depth. Provision is made for lubricating the bearings. With the exception of the straight knives I have described 30 substantially the whole of this machine in an earlier specification.

But in order that my invention may be more clearly understood I will now describe the same by aid of the accompanying illustrative drawings wherein:—

Fig. 1 is a vertical front elevation of the machine fitting with straight knives.

Fig. 2 is a sectional plan through the line 2—2 of Fig. 1.

45 In each of the illustrations similar letters of reference are used to denote similar or corresponding parts wherever they occur.

In the drawings *a* is a bench or platform through which a circular hole is cut as indicated by dotted lines and beneath which a chute *b* is arranged to receive and deflect waste material from the machine.

50 I construct from sheet metal or malleable cast metal or other material a frame or case *c* preferably of cylindrical formation, a portion of which is open as illustrated in the

drawings and along one edge of the open portion I provide a thickened portion *c'*. At the base of the cylinder I form legs or lugs preferably three in number as indicated 60 at *d* through which there is a hole for the foundation bolts *e* whereby the frame is secured to the bench.

Near to the base of the cylinder I also arrange a lower fixed spider *f* which may 65 form an integral portion of the casing or may be attached thereto by countersunk studs or screws or other convenient means and within this spider I form a cup *f'* to act as a bearing and I provide a ball race 70 therein.

At the top of the structure I arrange a corresponding bearing *g* which may likewise be provided with a ball race and can be secured by a screw threaded stud *g'* which 75 passes through the top of the structure and is held in position by the nuts *g''*.

For the purpose of mounting the cutting knives I furnish an upper and a lower rotatable spider *h* and *j* having central bearings 80 and being formed with enlarged attachment ends for the knives as indicated at *h'* and *j'* and being provided with bolts or studs *k* whereby the vertical knives *l* are adjustably secured to the spiders as illustrated. These 85 knives are preferably three in number and are arranged in the manner illustrated and may have their cutting edges slightly curved in the direction of their traverse as more clearly indicated at *l'* in Fig. 2 of the drawings as is the custom with fleshing knives, the direction of rotation being indicated by the arrow in Fig. 2.

The upper spider may have a short spindle seated therein adapted to be supported within the upper bearing. The lower spider is keyed or otherwise secured to a spindle *m* which may be adjustably held in position by the nuts *n* and extends downwardly below the bench or platform and is fitted with a 95 bevelled gear wheel *o* which registers with a bevelled gear wheel *p* mounted upon the horizontal driving shaft *q* which is supported by the bracket *r* and receives rotary motion from any convenient source of power. 100 This driving gear, however, may be varied 105 according to preferences and circumstances.

In the foregoing paragraph I have described the construction and arrangement of spindles and adjacent parts of such a nature 110 as to afford an easily fitted bearing which will offer very slight resistance and conse-

quently can be operated with low power, but it will be obvious that my rotatable vertical knife system may be mounted on a simple spindle without ball bearings if so desired 5 for cheaper types of machines.

Upon one side of the opening in the frame or case I mount a vertical flat sliding plate *s* having horizontal slots or slideways *s'* near each end thereof, and I also provide projecting studs *t* which are fitted with wing nuts *u* the studs being secured to the frame or case so that the vertical flat sliding plate when adjusted can be held in the desired position by the studs and wing nuts as will 15 be readily understood.

Upon the opposite side of the opening I arrange a vertical sliding plate *v* which may be concave so as to fit against the side of the cylindrical frame and is correspondingly 20 provided with slots or openings *v'* and wing nuts *w* adapted to serve as clamps when used in conjunction with the studs or bolts *t'*. By means of these sliding plates the effective depth of the cut of the knives can be 25 set according to preferences.

It is to be understood that the knives and the gear wheels can be set so as to rotate in the opposite direction to that which is illustrated in the drawings if so desired, the 30 sharpening and burring of the fleshing knives being correspondingly adapted.

In applying my invention to practical use the machine is set up as illustrated and the vertical flat sliding plates are drawn backwards or forwards and clamped in position 35 according to the amount of flesh to be removed from the skin or pelt.

The skin is then held by the operator using both hands so that when stretched out and 40 drawn tightly across the opening of the machine and allowed to bear against the edges of the sliding plates *s* and *v* the centre of the exposed area lies in the path of the rotat- 45 ing knives so that by drawing the skin or pelt backwards and forwards the flesh will be cut therefrom wherever exposed to the action of the knives.

If helical knives are used as in my former invention illustrated and described in my Patent No. 1,649,725 granted November 17, 50 1927 the skin or pelt will be drawn across the opening in a horizontal position, but if straight knives are used as herein described the skin or pelt should be moved in a diagonal direction. 55

It is intended that the operator should stand behind the machine, and the exposed edges of the sliding plates may be suitably bevelled for the more convenient and effective handling of the skin or pelt. The 60 interior of the machine is kept as open as possible so as to allow the cut flesh to fall through the space between the knives and spiders and be discharged through the bottom of the machine. 65

By providing these adjustment plates allowance is thereby made to enable the machine to be adapted to any inequality in the width of the cutting blades due to excessive wear or repeated sharpening, and the blades 70 themselves may be slightly slotted opposite to the bolts or studs *k* so as to enable them to be moved backwards or forwards as may be necessary, and it will be understood that the machine may be varied in size to suit 75 the different classes of skins or pelts which are to be fleshed thereby.

What I claim is:—

A fleshing machine having an outer frame or casing with an upright opening formed 80 therein, vertical adjustment plates mounted on the frame adjacent to each side of the opening, said plates being adapted to slide horizontally for adjustment purposes, a series of rotatably mounted vertical straight 85 knives arranged on a knife spider to rotate with the casing, and a lower bearing spider fixed within the frame and provided with a central bearing device in which the knife 90 spider is supported.

In testimony whereof I have affixed my signature.

RICHARD OLDS.
